TAPE-CONNECTED SLIDER FASTENER

Anthony W. Tripp and Jacob D. Stiriss, New York,
N. Y., assignors to Slidette Corp., New York,
N. Y.

Application February 8, 1940, Serial No. 317,840

17 Claims. (Cl. 24—207)

This invention relates to tape connected slider fasteners, and is particularly directed to slider fasteners of the character described for closing an opening having beads at the edges of the opening, slidably engaged by said fasteners, of the type generally disclosed in applicants' co-pending applications Serial Nos. 317,838 and 317,841, both filed on February 8, 1940.

An object of this invention is to provide slider fasteners of the character described, which will not cut the beaded edges and which will not grip the same either too tightly or too loosely, and which will not bind on said beaded edges.

Another object of this invention is to provide a slider fastener of the character described made of two parts, to one of which is attached an ornament or button, and to the other of which is separately attached a strip of tape, the parts having means for mutual inter-attachment after said ornament and tape have been attached to said parts.

A further object of this invention is to provide a slider fastener of the character described, which shall be easy to assemble, which shall be easy to attach to a strip of tape connecting said fasteners, and on which may be riveted a wide variety of ornamental members or buttons.

A yet further object of this invention is to provide a slider fastener of the character described made of two parts, having means to attach said parts together, said means also serving to attach a strip of tape to said fastener.

A still further object of this invention is to provide a slider fastener which may be made of die stamped metal parts, and in which both the tape and the ornamental or decorative button may be attached thereto by means of a riveting device, whereby the fasteners may be attached to the tape, and the buttons may be mounted on the fasteners quickly and inexpensively.

Still another object of this invention is to provide a strong and durable fastener construction of the character described, which shall be relatively inexpensive to manufacture, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which are

shown various possible illustrative embodiments of this invention,

Fig. 1 is a front elevational view of an opening in a garment having beaded edges at the opening and closed by a tape connected slider fastener construction embodying the invention;

Fig. 2 is a rear elevational view of the structure shown in Fig. 1;

Fig. 3 is a cross-sectional view taken on line 3—3 of Fig. 1;

Fig. 4 is a cross-sectional view taken on line 4—4 of Fig. 3;

Fig. 5 is a cross-sectional view taken on line 5—5 of Fig. 3;

Fig. 6 is a cross-sectional view taken on line 6—6 of Fig. 3;

Fig. 7 is a cross-sectional view taken on line 7—7 of Fig. 3;

Fig. 8 is a perspective view of a slider fastener embodying the invention, with the parts thereof separated;

Fig. 9 is a longitudinal, cross-sectional view through a slider fastener, embodying the invention, and illustrating a modified construction;

Fig. 9a is a rear elevational view of the structure shown in Fig. 9;

Fig. 10 is a cross-sectional view taken on line 10—10 of Fig. 9;

Fig. 11 is a cross-sectional view taken on line 11—11 of Fig. 9;

Fig. 12 is a view similar to Fig. 9, but illustrating a still further modified form of the invention;

Fig. 13 is a cross-sectional view taken on line 13—13 of Fig. 12;

Fig. 14 is a cross-sectional view taken on line 14—14 of Fig. 12; and

Fig. 15 is a perspective view of a modified form of tape connected fastener.

Referring now in detail to the drawings, 10 designates a garment or bag, or any other suitable construction having a longitudinal opening 10a. Stitched to the edges 11, 11 of the garment as at 11a, 11a, are elongated flexible strips 12, 12 provided with beading 14—14 at the adjacent marginal edges thereof.

Illustrated in the drawings, is tape connected slider fastener construction 15, embodying the invention, for attaching together the strips 12, 12 to close the opening 10a in the garment. Said slider fastener construction 15 comprises a plurality of spaced slider fasteners 16 interconnected by a longitudinal strip of flexible tape 17, in the manner described hereinafter.

Each slider fastener 16 comprises two parts 18 and 19, which may be made as metal die stamp-

ings, or in any other suitable manner. The part 19 has a flat wall 20 from the longitudinal edges of which extend parallel similar flanges 21, disposed at right angles to said wall. Wall 20 has a central recess 22 formed with a central opening 23 at the bottom thereof. The recess 22 is located between the flanges 21 and spaced therefrom, and extends in the same direction from the wall 20 as said flanges.

At the ends of the wall 20 are symmetrically disposed, recessed portions 26, each having a bottom wall 27 formed with a notch 28 at its outer end. The recesses 26 are likewise located between the flanges 21 and are aligned with the central recess 22.

The part 18 has a flat wall portion 30 formed with parallel flanges 31 extending at right angles thereto, and aligned with the flanges 21. Wall 30 is formed with a central opening 33, aligned with the opening 23 in recess 22. Extending from the ends of wall 30 are similar tabs 35, having reduced tongue portions 36 at their outer ends forming shoulders 37 at the base of the tongues.

In assembling the parts 18 and 19, the tongues 36 engage within the notches 28 and the shoulders 37 contact the walls 27 of the recesses 26. The tongues 36 are bent inwardly toward each other, to attach parts 18 and 19 together, and are hence disposed within the recesses 26. Thus, the shoulders 37 and the tongues 36 serve to space the walls 20 and 30, said walls being disposed in parallel relation. The flanges 21 and 31 are in alignment and spaced from one another, forming slots 38 therebetween.

The four corners of walls 20 and 30 are preferably cut-away, as shown at 18a and 19a, for the purpose hereinafter appearing.

The tape 17 may be riveted to part 19 by means of a riveted eyelet 40, passing through opening 22, said rivet having a flat head 41 extending transversely across the width of wall 20 to press the tape 17 thereagainst. Part of the tape is pressed into the recess 22 by said rivet. The outer edges 42 of the rivet head 41 may be slightly curved inwardly, as shown in Fig. 4 of the drawings, to press the tape 17 to part 19.

Attached to part 18 is an ornamental or decorative member or button 45 of any suitable construction. The button 45 may be attached to the part 18 by a riveted eyelet 46 fixed to said button and extending through the opening 33 of wall 30.

It will now be understood that the tape and the button may be separately riveted to the parts 19 and 18, respectively, and that said parts may thereafter be assembled together.

The cut-away corners 18a and 19a permit use of either a round or square or oblong button or ornament, without showing any part of the fastener.

As shown in Fig. 4 of the drawings, a cross-bar 50 may be attached to the slide fastener 16, said cross-bar being interposed between the button 45 and part 18, and having a central opening 51 through which the eyelet or rivet 46 passes. On the cross-bar 50 is a loop 50a, which may be grasped and pulled downwardly to bring the slide fasteners together at the bottom of the opening in the garment, to open up said opening in the garment. Upon pulling upwardly on loop 50a, the opening is closed.

If desired the part 18 may be formed with a central recess, similar to recess 22, and the button and tape may be attached to opposite sides of

the fastener 16 by a single rivet passing through the registering openings in the recesses. The recesses in parts 18, 19 should then be of a height sufficient to contact each other in order to maintain the proper spacing under the pressure of the rivet.

It will now be understood that the beads 14 are slidably engaged by the slider fasteners 16. The web portions of the strips 12 pass through the slots 38 formed between the flanges 21, 31.

In Figs. 9, 9a, 10 and 11, there is shown a slider fastener 16a comprised of two parts 60 and 61 which may also be made of metal die stampings. Part 60 has a flat wall 62 formed with a central opening 63. Extending from the sides of wall 62, are parallel flanges 64 disposed at right angles to said wall. Extending from the ends of wall 62 at right angles are tabs 62a having reduced inwardly bent tongues 62b at the ends thereof forming shoulders 63c, for the purpose hereinafter appearing.

Part 61 has a flat wall portion 66 formed with parallel flanges 67 aligned with and spaced from the flanges 64, to form slots 68 therebetween to receive the strips 12, the beaded edges 14 being disposed within the slider fasteners. Wall 66 is formed with a longitudinal, central recessed portion 70 forming a through groove, the bottom wall of which has a central opening 70a.

The bottom wall or recessed portion 70 is also formed with openings 70b adjacent the ends thereof. Tongues 62b pass through said openings 70b and pierce tape 17 thus serving to attach parts 60, 61 together and to attach the tape to the fastener 16a. Shoulders 62c of tabs 62a contact the underside of the recessed portion 70 to properly space walls 62, 66.

Attached to one side of the slider fastener 16 is an ornamental button 45a, and attached to the opposite side of said fastener, is the strip of tape 17. The button and the tape may be attached to the fastener by means of an eyelet 45b, fixed to the button 45a and passing through the central opening 63 in wall 62, and opening 70a in recessed portion 70, and receiving the stem of a rivet 71 engaged within said eyelet. The stem of said rivet pierces the tape 17 and is received within the eyelet 45b. The head of the rivet 71 presses a portion of the tape into the recess 70. The strip of tape 17 is thus fixed to fastener 16a at the ends by tongues 62b and at the middle by the rivet 71. This construction is suitable for relatively long fasteners.

In Figs. 12, 13 and 14, there is shown a slider fastener 16b, embodying the invention, and comprising parts 74 and 75 which may also be made as metal die stampings. Part 74 has a wall 76 formed with a central opening 77. At the outer ends of wall 76 are tabs 76 extending at right angles to said wall and formed with inwardly bent reduced tongues 85 forming shoulders 85a, for the purpose hereinafter appearing. Wall 76 is also formed with parallel flanges.

Part 75 has a wall 80 formed with flanges 81 aligned with the flanges 79 forming a slot therebetween to receive the strips 12. Wall 80 is also formed with a longitudinal depressed portion 82, forming a through groove, and the bottom wall of which is formed with openings 83 at the outer ends thereof.

The tabs 78 extend through the openings 83 and pierce the tape 17, and the inwardly bent portions 85 attach the parts 74 and 75 together, and also attach the tape 17 to the slider fastener 16b. An ornamental button 90 may be riveted

to wall 76 of part 74 by means of an eyelet rivet 91 passing through the opening 77 in said wall.

Sometimes it is necessary to mount relatively large ornaments on the tape connected fasteners, and if such ornaments were mounted one on each fastener, the ornaments would strike another or possibly become wedged. To overcome this difficulty one ornament is mounted on two fasteners 16, as shown in Fig. 15 of the drawings.

As illustrated in Fig. 15, a pair of adjacent fasteners 16 are interconnected by a longitudinal metal strip 95 having indentations 96 received within the recesses 22 of the fastener parts 19 and soldered thereto. The ornament 97 is fastened to the central portion of the strip 95, as at 98. The length of the strip 95 is preferably somewhat greater than the length of the ornament 97, to prevent adjacent ornaments from striking one another.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described our invention, we claim as new and desire to secure by Letters Patent:

1. A two part slider fastener, means on said parts for inter-attachment, a flexible tape attached to one part, and an ornamental member separately attached to the other part.

2. A slider fastener comprising two parts, means on said parts to attach one to the other, a strip of tape riveted to one part, and an ornamental button riveted to the other part.

3. A slider fastener comprising two parts, means on said parts to attach one to the other, an ornamental button riveted to one part, a strip of tape contacting the other part, and a rivet riveting said strip of tape to said other part, said rivet having a head formed with downwardly bent outer edges to clinch the tape to the side edges of said other part.

4. A slider fastener comprising parallel walls having aligned flanges extending toward each other, forming slots therebetween, one wall being formed with recessed portions at the ends thereof, tabs extending from the other wall and having shoulders contacting the bottoms of said recessed portions, and tongues extending from said tabs bent over into said recessed portions.

5. A slider fastener comprising parallel walls having aligned flanges extending toward each other, forming slots therebetween, one wall being formed with recessed portions at the ends thereof, tabs extending from the other wall and having shoulders contacting the bottoms of said recessed portions, and tongues extending from said tabs bent over into said recessed portions, the bottoms of said recesses having notches to receive said tongues.

6. A slider fastener comprising parallel walls having aligned flanges extending toward each other, forming slots therebetween, one wall being formed with recessed portions at the ends thereof, tabs extending from the other wall and having shoulders contacting the bottoms of said recessed portions, tongues extending from said tabs bent over into said recessed portions, one of said walls having a central recess formed with an

opening, a strip of tape contacting said wall, and a rivet passing through said opening to rivet said strip to said wall.

7. A slider fastener comprising parallel walls having aligned flanges extending toward each other, forming slots therebetween, one wall being formed with recessed portions at the ends thereof, tabs extending from the other wall and having shoulders contacting the bottoms of said recessed portions, tongues extending from said tabs bent over into said recessed portions, one of said walls having a central recess formed with an opening, a strip of tape contacting said wall, a rivet passing through said opening to rivet said strip to said wall, and an ornamental member riveted to said other wall.

8. A slider fastener comprising parallel walls having aligned flanges extending toward each other, forming slots therebetween, one wall being formed with recessed portions at the ends thereof, tabs extending from the other wall and having shoulders contacting the bottoms of said recessed portions, and tongues extending from said tabs bent over into said recessed portions, said recesses and tabs being located centrally between said flanges.

9. In combination, a slider fastener comprising two parts having parallel walls, and flanges on said walls, the flanges on one part being aligned with and spaced from the flanges on the other part, a flexible strip contacting one part, said part having openings, and tabs extending from said other part passing through said openings and piercing said strip and being bent over to attach said parts together and attach said fastener to said strip.

10. In combination, a slider fastener comprising two parts having parallel walls, and flanges on said walls, the flanges on one part being aligned with and spaced from the flanges on the other part, a flexible strip contacting one part, said part having openings, tabs extending from said other part passing through said openings and piercing said strip and being bent over to attach said parts together and attach said fastener to said strip, and an ornamental member riveted to said other part.

11. In combination, a two part slider fastener, one part having a longitudinal groove, the bottom wall of said groove having openings adjacent the ends thereof, a flexible strip contacting said part, said other part having tabs extending through said openings and piercing said strip and being bent over into said groove to attach said parts together and to attach said strip to said fastener.

12. In combination, a two part slide fastener, one part having a longitudinal groove, the bottom wall of said groove having openings adjacent the ends thereof, a flexible strip contacting said part, said other part having tabs extending through said openings and piercing said strip and being bent over into said groove to attach said parts together and to attach said strip to said fastener, said other part having an opening, and a button riveted thereto by a rivet passing through said last opening.

13. In combination, a slider fastener comprising two parts having parallel walls, and parallel flanges on said walls extending at right angles to said walls, the flanges on one wall being aligned with and spaced from the flanges on said other wall, means on said parts to attach said parts together with said walls in spaced parallel relation, said means being located be-

tween said flanges, an ornamental member fastened to one wall by a rivet, and a flexible strip attached to said other wall by a separate rivet.

14. In combination, a slider fastener comprising two parts having parallel walls, and parallel flanges on said walls extending at right angles to said walls, the flanges on one wall being aligned with and spaced from the flanges on said other wall, means on said parts to attach said parts together with said walls in spaced 10 parallel relation, said means being located between said flanges, an ornamental member fastened to one wall by a rivet, and a flexible strip attached to said other wall by a separate rivet, said last rivet having an oblong head with bent 15 ends contacting the outer surface of said strip and overlapping the part to which it is riveted.

15. In combination, an elongated flexible tape, a plurality of fasteners fixed thereto, a member interconnecting each adjacent pair of fasteners, 20

and an ornament fixed to an intermediate portion of each member.

16. In combination, a pair of strips having marginal beaded edges, a plurality of fasteners having means to slidably receive said beaded edges, a tape fastened to said fasteners, a member interconnecting each pair of adjacent fasteners, and an ornament mounted on an intermediate portion of each member.

17. In combination, an elongated flexible tape, a plurality of fasteners fixed thereto, a member interconnecting each adjacent pair of fasteners, an ornament fixed to an intermediate portion of each member, each fastener having a recess, and each member having a pair of spaced projections engaged within the recesses of the pair of fasteners fixed to said member.

ANTHONY W. TRIPP.
JACOB D. STIRISS.
